HEEL BREASTING MACHINE

Lawrence Mawbey, Leicester, England, assignor to United Shoe Machinery Corporation, Flemington, N. J., a corporation of New Jersey

Application January 2, 1952, Serial No. 264,443

Claims priority, application Great Britain January 23, 1951

24 Claims. (Cl. 12—47)

1

This invention relates to machines for use in the breasting of built-up leather heels, it being an object of the present invention to produce an improved machine of the general type disclosed in United States Letters Patent No. 2,530,590, granted November 21, 1950, on an application filed in the names of Percy White and Frank B. Keall.

The present invention consists in the novel features hereinafter described, reference being had to the accompanying drawings which illustrate one embodiment of the invention selected for purposes of illustration, said invention being fully disclosed in the following description and claims.

In the accompanying drawings,

Fig. 1 is a perspective view, partly broken away, of the illustrative machine;

Fig. 2 is a side elevation, partly broken away and partly in section, of the machine;

Fig. 3 is a plan view, partly broken away, of the machine;

Fig. 4 is a rear view of the upper portion of the machine showing in detail mechanism for guiding and actuating a breasting knife of the machine;

Fig. 5 is an enlarged front view of part of the machine a casing of which has been broken away to show mechanism for rotating a heel supporting turret of the machine;

Fig. 6 is a plan view, partly broken away, showing portions of mechanism for operating heel holding and positioning instrumentalities of the machine;

Fig. 7 is a front view of one of two heel holding units forming part of the turret of the machine, a cover for said unit having been removed;

Fig. 8 is a side elevation, partly in central vertical section, of one of the heel holding units;

Fig. 9 is a view on line IX—IX of Fig. 5;

Fig. 10 is a view on line X—X of Fig. 6 showing portions of mechanism for controlling the operation of the heel holding units at a loading station of the machine and the actuation of indexing mechanism for the turret;

Fig. 11 is a front view of a modified heel gripper which may be substituted for a heel gripper of one of the above-mentioned heel holding units;

Fig. 12 shows in elevation safety mechanism for insuring that the turret is clear of any articles which may be accidentally left on the turret and which during the breasting operation would otherwise be engaged by the breasting knife and/or its operating mechanism;

Fig. 13 is a front view of the left half of the safety mechanism illustrated in Fig. 12; and

Fig. 14 is a front view of a clutch which may be advantageously used in the machine.

2

The illustrative machine is described with reference to breasting built-up leather heels 20 (Fig. 8) and comprises a turret 22 having two heel receiving or holding units 24 which are intermittently indexed 180° between a heel loading station 26 (Figs. 1, 2 and 3), at which the heels are positioned and gripped in the forward of two units, and a heel breasting station 28 in which the heels, clamped securely in the rear unit, are breasted by a vertically reciprocable breasting knife 30 operating against wooden cutting blocks 32 of the units successively indexed to the breasting station.

The heels 20 are successively positioned lengthwise in the holding units 24 at the heel loading station 26 by a breast gage 34 (Figs. 1, 3 and 8) which is movable to and from an active position over an associated cutting block 32 which forms part of the unit and part of a platform or table 36 of the turret 22, said breast gage having a convex forward edge 38 shaped and arranged, when in a forward or active position, to be engaged by a concave breast face 40 (Fig. 8) of the top lift 42 of the heel.

Each of the heel receiving or heel holding units 24 (Figs. 7 and 8) also comprises a pair of grippers 44 carried by levers 45 which are movable in slots 46 (Figs. 1, 3 and 6) formed in the platforms 36 of the turret 22 and which are geared together for equal and opposite movement and are constantly urged toward each other by springs 48. As the grippers 44, rendered active as a treadle 50 is initially depressed, move toward each other under the action of the springs 48, they engage opposite sides of the heel a short distance (approximately $\frac{3}{8}$ ") above the block 32 and centralize and thereafter grip and penetrate to a slight extent the heel the breast face 40 of the top lift of which is in engagement with the breast gage 44 as shown in Fig. 8.

Each of the heel holding units 24 also comprises an angular cover 52 which is secured by screws 54 (Figs. 1 and 5) to the turret 22 and comprises a lid portion which fits in a recess 56 of the platform 36 of the turret and is spaced slightly from the associated cutting block 32, an apron portion of the cover serving to encase hereinafter described gripper actuating mechanism of the turret. The platform or table 36 of the turret 22 may be described as comprising the cutting block 32 as well as the lid portion of the angular cover 52.

After the heel 20 has been positioned and clamped in one of the heel holding units 24 at the heel loading station 26 in response to initial depression of the treadle 50, the breast gage 34

upon continued depression of the treadle, is swung rearward to a retracted position and a one-revolution clutch 96 (Fig. 14) hereinafter described is actuated to index the turret 22 through 180°, the grippers 44, which at that time are forced against and penetrate to a slight extent the heel, being forced downward during the first part of said indexing movement by compression springs 58 (Figs. 7 and 8) rendered active to clamp the heels securely against the cutting block 32.

During the first half of the cycle of the machine the heel in the heel holding unit 24 at the loading station 26 is indexed 180°, said unit arriving at the breasting station 28 and coming to rest. During the second half of the cycle of the machine the breasting knife 38 is rendered active to breast the heel in the heel holding unit 24 at the breasting station 28 and during this time another heel is placed in the other heel holding unit then positioned at the loading station 26. After the heel holding unit 24 in which the heel 20 has been breasted has been indexed a few degrees from the breasting station 28 the grippers 44 are forced away from the heel against the action of the springs 48 and as the unclamped heel is indexed with the turret it is knocked at an ejecting station 59 (Figs. 1, 2 and 3) into a chute 60, which is formed in a bracket 62 secured to and constituting part of one of a pair of side frames 64 of the machine, by an arm 66 of an ejector 68. Chips (not shown) trimmed from heels 20 during the heel breasting operation drop for disposal into a large central passage 70 extending heightwise through the turret.

The illustrative machine comprises a housing 72 (Figs. 1 and 2) within which are included various driving and controlling mechanisms of the machine. The housing 72 comprises the side frame 64 and a central frame 74 which is bolted or otherwise secured to the side frame, the central frame supporting most of the driving and controlling mechanisms of the machine. Secured to the side frames 64 of the housing 72 at the rear base portion of the machine is an electric motor 76 (Fig. 2) which is operatively connected by belts 78 to a driving pulley 80 journaled upon a bearing shaft 82 secured to the central frame 74. The driving pulley 80 has pinned to it a gear 84 meshing with a gear 86 rotatably mounted upon a clutch shaft 88 which is rotatably mounted in the central frame 74 and has secured to its forward end a gear 90 meshing with a gear 92 secured on a driving shaft 94 rotatably mounted in the central frame and arranged parallel to the clutch shaft 88. The gear 86 is operatively connected to the shaft 88 by the one-revolution clutch 96 (Fig. 14) tripped in response to movement of a bell-crank lever 98 (Figs. 2, 5, and 14) which is connected to the treadle 50 and will be hereinafter described in detail, said clutch being automatically disengaged after each cycle of the machine even though the treadle 50 is held depressed. The driving shaft 94 has secured to it a gear 100 which meshes with a gear 102 secured to a countershaft 104 rotatably mounted in the central frame 74, the construction and arrangement of the gears 100, 102 respectively connecting the driving shaft and the countershaft being such that the countershaft rotates once and the driving shaft twice during each cycle of the machine.

The turret 22, which comprises a downwardly extending sleeve 106 (Figs. 2, 3 and 5) having secured to it a flange 108, is mounted in upper

and lower bearings 110, 112 formed in the central frame 74, said turret being rotatable about an axis 114 and being intermittently indexed clockwise, as viewed from above, 180° about said axis to move the heel holding units 24 between the heel loading and breasting stations 26, 28 during the first half of each cycle of the machine. Secured to the sleeve 106 by pins 116 (only one shown) is a collar 118 (Fig. 2) having extending laterally from its opposite sides abutments 120 (Figs. 2 and 6) which are alternately engaged by a pawl 122 pivoted upon a pin 124 forming part of a pawl carrier 126 rotatable upon the sleeve and arranged between the collar 118 and the lower bearing 112, the pawl being constantly urged toward the collar 118 by a torsion spring 127.

Secured to the lower end of the pawl carrier 126 is a bevel gear segment 128 (Fig. 2) meshing with a gear segmnt 130 (Figs. 2 and 5) on a lower end of a table actuating arm 132 which is secured to the front end portion of a spindle 134 rotatably mounted in the central frame 74. The table actuating arm 132 has pivotally connected to it the upper portion of a link 136 the lower end of which is pivoted to a crank pin 138 carried by a crank 140 secured to the front end of the countershaft 104. During each revolution of the countershaft 104 the table actuating arm 132 is caused to move to and fro through 90°, the ratio between the gear segments 128, 130 being such that the pawl carrier 126 moves 180° and back again about the axis of rotation 114 of the turret 22. During the rotation of the pawl carrier 126 in a clockwise direction, as viewed from above, the pawl 122 moves one of the abutments 120 and accordingly the turret 22 through 180° and returns in readiness to move the other abutment 120 during the next movement of the pawl carrier. The turret 22 is, therefore, rotated in a clockwise direction through one-half a revolution each time the countershaft 104 rotates once and, as will be hereinafter explained, carries the heel positioned and clamped in the heel holding unit 24 at the loading station 26 to the heel breasting station 28 at which the knife 38 operates upon the heel. As above explained, during the indexing of the turret 22 the heel which has been breasted in the heel holding unit 24 at the breasting station 28 is released and ejected into the chute 60 as such unit returns to the loading station 26 to receive another heel.

Each heel holding unit 24 (Figs. 7 and 8) (the unit at the loading station 26 is illustrated in detail) comprises a box-like bracket 142 which is secured by screws 144 to the sleeve 106 of the turret 22 and has secured to and covering it the angular cover 52. As above stated, the platform 36 has formed in it the recesses 56 into which the platform portions of the angular covers 52 fit, said platform portions of the covers, as best shown in Fig. 8, being spaced slightly from associated wooden cutting blocks 32 to provide the continuations of the slots 46 in which the gripper carrying levers 45 move. The upper ends of the levers 45 (Fig. 7) have dovetail portions 146 fitting in dovetail slots 148 formed at the bottoms of heel gripper carriers 150 having secured to them opposing sharp prongs 152 arranged to engage and penetrate the opposite sides of the heel placed upon the wooden block 32 with its breast in engagement with the breast gage 34, said carriers being secured to the levers by screws 154. The pins 152 are used to adapt the machine for handling relatively low heels. If high heels are to

be operated upon the above-described gripper carriers 150 are replaced by carriers 150A (Fig. 11) having prongs 152 positioned substantial distances above the cutting block 32 thereby insuring against the heel being tipped lengthwise during the breasting operation.

The gripper carrying the bell crank levers 45 are pivotally mounted upon parallel bearing pins 156 (Figs. 7 and 8), which are secured to a bar 158, opposing ends of horizontal arms of the bell crank levers having meshing gear teeth 160 for effecting equal and opposite angular movement of said bell crank levers about their associated bearing pins. The bar 158 has secured to it and extending downwardly from it a vertical rod 162 which is reciprocable in a vertical bore 164 (Fig. 8) of the bracket 142 and has rotatably mounted upon its lower end portion a cam roll 166 (Figs. 5, 7 and 8). The bar 158 and the vertical rod 162 secured to it may be described as a slide for carrying the bell crank levers 45. The right-hand bell crank lever 45 (as viewed from the front of the machine) comprises an arm 168 which is arranged in front of and parallel to its geared arm and which is pivotally connected to the upper end of a vertical link 170, the lower end of which is pivotally connected to a substantially horizontal arm of a bell crank lever 172 pivoted on a horizontal stud 174 secured to the bracket 142. An upstanding arm of the bell crank lever 172 has pivoted to its upper end portion an adjusting rod 176 passing freely through the upper end portion of an upstanding arm of a bell crank lever 178 which is pivoted on the stud 174 and has a horizontal arm carrying a cam roll 180. The adjusting rod 176 has threaded onto it a thumb nut 182 which constantly engages the upstanding arm of the bell crank lever 178.

When the heel receiving or holding units 24 are at the loading station 26 the cam roll 166 carried by the vertical rod 162 is forced under considerable pressure by the compression springs 58, which are interposed between the bracket 142 and the bar 158, against the upper face 186 of a gripper raising cam 188, which is secured by screws 190 to the central frame 74, and the bell crank levers 45 and accordingly the gripper carriers 150 are held in raised positions with relation to a work engaging face 192 of an associated cutting block 32. Furthermore, the cam roll 180 on the lever 178 is forced by the tension springs 48, opposite ends of which are connected to studs 194 secured to the bell crank lever 45 and to studs 196 extending forwardly from the lower ends of the rod 162, downward against a then raised supporting face 198 (Figs. 6, 7 and 8) of a gripper opening lever 200 secured on a spindle 202 rotatably mounted in a bracket 204, which is secured by screws 206 to and forms part of the center frame 74. Accordingly, when the holding units 24 are at the loading station 26 the grippers 44 are held in open positions so that the heel to be breasted may be placed between them in said units 24. When the grippers 44 are in their raised open positions the thumb nut 182 is commonly rotated to vary the gap between the grippers in accordance with the width of the heel, it being customary to adjust the grippers so as to enable the heel to be inserted between the grippers with a slight amount of clearance.

The gripper opening lever 200 has formed in it a recess 208 (Figs. 6 and 8) for receiving a compression spring 210 which engages the bottom of the bracket 204 of the side frame 14 and constantly urges the supporting face 198 of said lever

upward. The tension springs 48, however, are stronger than the compression springs 210 and tend to depress the supporting face 198 of the lever. When the heel holding units 24 of the turret 22 are at the heel loading station 26 depression of the face 198 of the lever 200 is prevented by the engagement of a forward stepped portion 212 (Figs. 6, 7 and 8) of a control rod 214, which is mounted for forward and rearward sliding movement in guideways 216 of the fixed bracket 204, with the upper face of a block 218 secured by screws 220 to the gripper opening lever 200. Pinned to the rear end portion of the control rod 214 is a collar 222 (Figs. 6 and 10) in which is formed a circumferential groove 224 having engaging in it pins 226 (Fig. 6) secured to a forked arm of a bell crank lever 228 (Figs. 6 and 10) keyed to a spindle 230 rotatably mounted in the central frame 74. Another arm of the bell crank lever 228 is operatively connected by a rod 232, and other mechanism hereinafter described, to the treadle 50.

As the treadle 50 is depressed preparatory to tripping the clutch for starting the machine, the stepped portion 212 of the control rod 214 is moved rearward from its position above the block 218 which is secured to the gripper opening lever 200 with the result that the springs 48 cause the grippers 44 to move into engagement with the opposite sides of the heel placed in the heel holding unit 24 at the loading station 26.

Further depression of the treadle 50 causes the clutch 96 to be tripped and as the turret 22 rotates the cam roll 180 on the lever 172 moves away from the supporting face 198 of the lever 200 and the cam roll 166 on the lever supporting rod 162, which together with the bar 153 may be referred to as a carrier, moves away from the cam block 168 after the turret has rotated a few degrees from its indexed position with the result that the grippers 44 are lowered from their elevated position by the compression springs 53 to depress the heel against the platform.

If, after a heel 20 has been placed in the holding unit 24 and the treadle 50 has been partially depressed to withdraw the control rod 214 from its locking position over the block 218 to allow the grippers 44 to be moved from their open position against the heel, the operator is not satisfied that the heel is correctly positioned, said grippers may be readily opened by raising, as viewed in Fig. 7, a manually operable arm 233 secured to the spindle 202 thereby rotating the lever 200 clockwise and causing the surface 192 on the lever to press up on the roll 188 so that the grippers will be separated to release the heel. The heel may then be repositioned upon the holding unit 24 and the manually operable arm 233 released to allow the tension springs 48 again to close the grippers against opposite sides of the heel. The grippers 44 may be described as movable equal distances in opposite directions in paths generally parallel to the heel engaging face 192 of the block 32 of the associated unit and also as movable together or collectively in a path disposed at right angles to said first-named paths. The springs 48, 58 may be described as portions of mechanisms for causing the grippers 44 to apply primary and final clamping pressures respectively against the heel.

The wooden cutting block 32 (Fig. 7) of each of the heel holding units 24 is supported upon a wedge member 234 having faces 236 which engage inclined faces 238 of the box-like bracket

142, the wedge member being moved and held in different adjusted positions upon the wedge faces of said bracket by a screw 249 which is rotatably mounted in an undercut slot 242 of the bracket and is threaded into the box-like bracket 142 of the machine. By rotating the screw 249 the cutting block 32 may be readily adjusted until its work engaging face 192 is flush or in alinement with the upper face of the platform 38 of the turret 22.

The breast gage 34 which, after the heel upon the turret 22 has been seized by the grippers 44 and before the turret commences to rotate, is moved away from its active or gaging position above the cutting block 32 of the holding unit 24 at the loading station 26 so as not to interfere with the gripped heel as it is moved away from the loading station, will now be described. The breast gage 34 (Figs. 1, 3 and 8) has secured to it pins 244 which pass through openings in eyebolts 246 (Fig. 3) carried by a breast gage arm 248 and have collars 250 secured to their upper ends to retain the pins on the eyebolts. The eyebolts 246 pass through a lower end portion of the breast gage arm 248 and may be moved into different forward and rearward adjusted positions in said arm by thumb nuts 252 threaded onto the eyebolts and having flanges which fit in recesses 254 of said arm. A compression spring 256 opposite ends of which engage respectively the breast gage arm 248, and a lug 258 extending upward from the breast gage 34 is adapted to hold the eyebolts 246 firmly in their adjusted positions against said arm.

The breast gage arm 248 is pinned to a horizontal shaft 260 (Figs. 1, 2 and 3) rotatably mounted in the bracket 62 which, as above stated, is secured to the right side frame 74 and has formed in it the chute 60 into which the breast-heels are knocked and which may be described as being positioned at the ejecting station 59. Also secured to the shaft 260 is an arm 262 pivotally connected to the upper end of a rod 264 which is guided in a recess 265 in the side frame 64 and has mounted on its lower end a roll 266 forced, by means hereinafter described, against a two-part rod 268 (Figs. 1, 2, 5, 6 and 10) a forward portion of which is adjustable with relation to a rear portion thereof. The front portion of the rod portion 268 is slidably mounted in a guideway 270 (Figs. 5 and 6) in the side frame 74 and the rear portion of the rod has formed in it a slot 272 (Fig. 10) through which passes a pin 274 secured in an arm 276 keyed to the spindle 230. As will be explained later, in order, during the first part of the downward movement of the treadle 50, to cause the grippers 44 to seize the heel without effecting movement of the breast gage 34 the pin 274 moves idly along the slot 272 until it engages an adjustable screw 278 threaded into the rear portion of the rod 264 and accordingly thereafter forces said rod rearward to permit the breast gage to be moved rearward by spring action from its gaging position.

The roll 266 of the rod 264 is normally held by a tension spring 280 (Figs. 1 and 3), which is connected to the breast gage arm 248 and to a pin secured to the bracket 62, against a portion 282 (Fig. 6) of large diameter of the two-part rod 268 and when the two-part rod is moved rearward, by mechanism hereinafter described, the roll 266 on the lower end of the rod 264 moves down into engagement with a portion 284 of reduced diameter of the two-part rod and accord-

ingly causes the breast gage 34 to be moved rearward about the axis of the shaft 260 by the action of said spring 280. The two-part rod 268 is constantly urged toward its forward position 5 shown in Fig. 6 by a tension spring 286 opposite ends of which are attached respectively to a stud 288 secured to the side frame 64 and to a stud 290 secured to the rod, the stud 290 being held against a stop 292 secured to the side frame. 10 After initial depression of the treadle 50 during which the grippers 44 are moved into engagement with the heel and the lost motion provided by the slot 272 in the two-part rod 268 has been taken up, further depression of the treadle, before tripping the clutch, causes the two-part rod 15 to be moved rearward thereby allowing the roll 266 (Fig. 5) on the rod 264 to be moved downward by the tension spring 280 against the reduced portion 284 of the two-part rod and the breast gage 34 to be moved rearward so that a heel between the grippers may be indexed without interference with said gage. The two-part rod 268 is held in its rearward position until the heel has been breasted by a spring actuated latch 294 pivoted upon the rod 268 and arranged to engage a flat face 296 formed on the stop 292. The breast gage 34 is returned to its active position 20 shown in Figs. 1 and 3 against the pull of the tension spring 280 by the action of the spring 286 after the release of the latch 294 from the stop 292.

The latch 294 is released from the stop 292 by a screw 298 adjustably secured to an arm 300 fixed to a vertical shaft 302 (Figs. 2, 3 and 6) rotatably mounted in extensions of a bracket 304 (Figs. 1, 2, 3 and 4) secured by screws 306 to the side frame 64. The vertical shaft 302 also has secured on it an arm 308 (Figs. 2 and 3) which carries a roll 310 held, by mechanism hereinafter described, against an edge face 312 of the platform 36 of the turret 22.

The rod 232 is operatively connected to a treadle rod 314 (Figs. 2, 5 and 9) which is lowered against the action of a treadle spring 315 (Fig. 2) in response to depression of the treadle 50, the construction and arrangement, as will be explained later, being such that the connection between the treadle rod and the rod 232 is broken soon after the machine commences to operate by power. Accordingly, the rod 214, which renders the grippers 44 active and inactive, may be moved forward by a spring 316 (Fig. 6) forward and rear ends respectively of which are connected to the side frame 64 and to a stud 318 carried by the arm 276, even though the treadle is held depressed, until the machine stops.

The rod 232 is connected to the treadle rod 314 through a block 320 secured by a screw 322 to the rod 232, the block having a passage 319 (Fig. 9) 60 formed in it for the treadle rod 314 the upper end of which is guided by the block and which has a shoulder 324 (Fig. 5) arranged when the machine is idle to engage the upper face of the block. When the treadle rod 314 is depressed the shoulder 324 causes the rod 232 also to be depressed and the control rod 214 to slide rearward out of contact with the gripper opening lever 289. The lower end portion of the rod 232 passes freely through a bore 326 in a block 328 pivoted in an arm of the bell crank lever 93 another arm of which is pivotally connected to a link 339 (Figs. 2 and 14) for controlling the one-revolution clutch 96 to operate the machine through one cycle. After the rods 214, 268 have been moved rearward by mechanism above described

to effect the seizing of the heel by the grippers 44 and the moving of the breast gage 34 away from the positioned and seized heel, further depression of the treadle 50 causes the block 320 to depress the block 328 with the result that the clutch 96 is tripped and the machine is power operated through a cycle and comes to rest.

Soon after the machine is power operated the shoulder 324 (Fig. 5) overlying the upper face of the block 320 is disengaged from said face by the engagement of a cam 332 (Figs. 2 and 5) on the countershaft 104 with a roll 333 (Figs. 5 and 9) carried by the treadle rod 314 thereby enabling the rod 232 to be raised by the spring 316 (Fig. 6) even though the treadle 50 is held depressed. After the treadle 50 is released and the treadle rod 314 has been moved to its raised position by the treadle spring 315 said rod, the upper end of which is guided by the block 320, is swung to the right, as viewed in Fig. 5, by said treadle spring causing the shoulder 324 of the treadle rod to overlie the upper face of the block 320.

As above explained, after the heel in the holding unit 24 at the breasting station 28 has been breasted the turret 22 is indexed and just before the breasted heel reaches the ejecting station 59 the grippers 44 are moved away from the heel to release it in response to engagement of the cam roll 180 on the bell crank lever 178 with a cam face 336 (Fig. 6) which is formed on the bracket 204. The breasted heel is ejected from the holding unit 24, from which it has been released, by the knock-off arm 66 (Fig. 1) which strikes the breast of the heel and knocks said heel off the turret platform 36 and into the chute 60. The knock-off arm 66 is pivotally mounted upon a pin 340 carried by a lever 342 (Figs. 1 and 3) which is pinned to a bearing spindle 344 rotatably mounted in the bracket 62. An upstanding arm of the lever 342 has pivotally connected to it one end of a link 346 the other end of which is pivotally connected to an arm 348 secured to the vertical shaft 392 (Figs. 2, 3 and 6).

The platform edge face 312, which includes edge faces of the angular covers 52, has formed in it two diametrically opposite arcuate openings 350 into which the roll 310 on the arm 308 swings during the indexing of the turret 22. Each arcuate opening 350 has its leading end formed in a trailing edge face of the corresponding angular cover 52 off which the roll 310 is forced to a position beneath the platform 36 by a spring 352 (Figs. 1 and 3) one end of which engages a lug of the bracket 62 and the other end of which engages a head of a rod 354 which passes through the spring and through a bore 356 of the lug and which is pivotally connected to an upstanding arm of the lever 342. The knock-off arm 66 swings between the grippers 44, which have been previously moved away from each other, to release the heel, and knocks the heel off the platform 36, a leather faced lug (not shown) on the bracket 62 serving to stop ejecting movement of the lever 342.

Secured by screws 358 (Figs. 3, 5 and 6) in the trailing end portions of the openings 350 are cam blocks 360 arranged to engage the roll 310 of the arm 308 and to return the knock-off arm 66 against the action of the spring 352 back to the retracted position shown in Fig. 1. The turret 22 is being indexed while the knock-off arm 66 ejects the breasted heel from the turret 22, the cam blocks 360 being so arranged that the holding units 24 from which the heels are ejected have

passed the ejecting station 59 at the time the knock-off arm is returned to its retracted position. The knock-off arm 66 is normally held in its normal position shown in Fig. 1 upon the pin 340 by a spring 366 the upper end of which is attached to a pin on the bracket 62 and the lower end of which is attached to a pin secured to the upper end of said knock-off arm. Should the knock-off arm 66 during the ejection of the heel be accidentally engaged by one of the grippers 44, said arm will yield about the pin 340 against the action of the spring 366 under the pressure of said gripper, said knock-off arm returning to its normal position again when it has been moved out of engagement with the gripper.

It will be noted that clockwise movement (Fig. 3) of the arm 308 in response to movement of the roll 310 into either of the openings 350 of the turret 22 causes the screw 298 (Fig. 6) to move the latch 294 away from the stop 292 and thus enables the two-part rod 268 to move forward under the action of the spring 286 to its starting position thereby causing the breast gage 34 to be moved against the action of the spring 280 back to its forward, active or gaging position. Prior to releasing the latch 294 the cam 332 (Fig. 5) will have moved the shoulder 324 of the treadle rod 314 away from the upper surface of the block 320 to release the rod 232, thereby allowing the control rod 214 acted on by the spring 316 to be moved to its forward position over the block 218 of the gripper-opening lever 200 upon movement of the two-part rod 268 to its forward position.

The breasting knife 30 is secured to a knife slide or holder 370, which is reciprocated in a knife guide or frame 372, by a clamp arm 368 and associated pressure equalizing mechanism which is similar to that disclosed in the above identified Patent No. 2,530,590 and need not be described herein in detail. In order to vary the angles of the breast faces of heels with relation to the tread faces of said heels the knife guide or frame 372 is initially adjustable into different active positions about an axis 374 (Figs. 2 and 3) extending generally transversely of the heel along the face 192 of the cutting block 32 and passing approximately through the point of engagement of a central portion of a cutting edge 376 of the knife and said face of the block. The axis 374 may also be described as lying in the face 192 of the platform or the cutting block 32 and as extending transversely of the heel in the vicinity of its breast. In order to effect angular adjustment of the knife frame 372 about the axis 374 said frame has secured to it a pair of arcuate flanges 378 (Figs. 1 and 2) which are initially adjustable along curved guideways 380 a common center of curvature of which coincides approximately with the axis 374. The lower faces of the guideways 380 are formed by the main casting of the knife bracket 304, upper faces of said guideways being formed by lower faces of arcuate bars 382 which are secured by screws 384 to the main casting of the knife bracket 304 and may be considered parts of the bracket. Formed on the upper surfaces of the arcuate bars 382 are gear teeth 386 meshing with pinions 388 secured to a horizontal shaft 390 extending laterally of the machine and rotatably mounted in bearings 392 (Figs. 3 and 4) forming part of the knife frame 372. The right-hand portion of the shaft 390, as viewed from the front of the machine, is hexagonal at 394 so that a handle (not shown) may be placed thereon and the shaft rotated, rotation of the shaft in a clockwise direction as viewed

from the right of the machine, causing the pinions 388 to roll rearward and downward along the gear teeth 396 and the knife 372 to be adjusted about the axis 374 to vary the path of reciprocation of the knife with relation to the heel engaging face 192 of the cutting block 32.

The knife frame 372 may be secured in its adjusted position upon the bracket 304 by the engagement of a tooth 396 (Fig. 4) on the lower end of a detent 398 (Figs. 3 and 4) between adjacent teeth of the right pinion 388, said detent being slidably mounted in a guideway of a boss of the knife frame and having in its upper end portion a recess 400 which is engaged by an eccentric portion 402 of a pin 404 rotatably mounted in said boss. The pin 404 has secured to it a handle 405 by which the pin may be rotated to raise the tooth 396 of the detent 398 away from its associated pinion 388 preparatory to adjusting the knife frame 372 about the axis 374 or to move the tooth of the detent into engagement with teeth of the pinion to maintain the knife frame 372 in its adjusted position.

To prevent the knife frame 372 from falling rearward along the arcuate guideways 383 in the event that the tooth 396 on the detent 398 be withdrawn from engagement with teeth of the pinion 388 and the handle (not shown) connected to the gear shaft 390 shall be accidentally released by the operator, a friction device 406 (Fig. 4) is arranged permanently to engage the gear shaft. The friction device comprises two blocks 408 each having a leather lined surface (not shown) for engaging the shaft, said blocks being adjustable toward each other by screws 410 passing through one block and threaded into the other. The blocks 408 are prevented from rotating upon the shaft 390 by a pin 412 secured to the knife frame 372 and engaging in a recess of one of the blocks.

The upper end portion of the knife slide 370 has journaled in it a laterally extending horizontal shaft or pin 414 (Figs. 1, 3 and 4) on eccentric end portions 415 of which are mounted links 416 extending downward one at each side of the knife frame 372. The lower end portions of the links 416 are pivoted on coaxial pins 418 (Figs. 1, 4 and 13) extending laterally of the machine and secured to the front end portions of arms of a knife actuating lever 420 (Figs. 2, 3, 4, 12 and 13) which is journaled upon a horizontal bearing rod 422 secured to the knife bracket 304.

The knife actuating lever 420 has two rearwardly extending arms to which are pivoted a pair of thrust bars 424 the lower ends of which, when the bars are swung rearward by mechanism hereinafter described, engage in recesses 426 formed in a T-shaped actuator 428 having a shank which is slidably mounted in a vertical guideway 430 of the bracket 304. The actuator 428 is pivotally connected to the upper end portion of a connecting rod 432 driven by a crank 434 (Fig. 2) on the drive shaft 94.

The thrust bars 424 are pivotally connected to bifurcations of a link 436 (Figs. 2, 3, 4 and 5) pivotally connected to the upper end of an arm 438 (Figs. 2 and 5) keyed to a horizontal spindle 440 which is rotatably mounted in bearings of the central frame 74 and has secured to it a lower arm 442 carrying a cam roll 444 constantly forced by a spring 445 (Fig. 2) against a cam 446 secured to the countershaft 104.

When the thrust bars 424 are in engagement in recesses 426 of the actuator 428 rotation of

the drive shaft 94 causes the crank 434 thereon as it rises to move the knife actuating lever 420 counterclockwise as view in Fig. 2 and the knife 30 to descend.

As the crank 434 descends tension springs 448, upper and lower ends of which are attached to the rear arms of the knife actuating lever 420 and to the central frame 74 respectively, raise the knife slide 370 and accordingly the knife 30 cause the thrust bar 424 to bear against the bottoms of the recesses 426 and to move downward with the actuator. By the above means the speed of upward movement of the knife 30 is controlled and the knife is prevented from being raised undesirably fast. Just before the crank 434 reaches its lowermost position a lug 450 (Figs. 2, 3, and 4) extending rearward from the knife slide 370 and projecting rearward through an opening in the knife frame 372, engages an adjustable stop screw 452 threaded into the knife frame and when the crank has reached its lowest position a small clearance is provided between the lower ends of the thrust bars 424 and the recesses 426 in the actuator 428 so that said bars may be readily disengaged from the recesses.

The shaft 414 which carries the knife slide 370 may be rotated initially to adjust the knife 30 with relation to the links 416 which, as above stated, are pivotally connected to the eccentric portions 415 of the shaft. The shaft 414 has secured to it an arm 454 into which is threaded a locking screw 456 having a tapered end portion 458 (Fig. 3) arranged to engage a V-shaped groove 460 extending around a collar 462 which is mounted upon the shaft and is held from rotation with relation to the knife slide 370, which may be considered as part of the knife, by a lug 464 formed on the collar and fitting in a groove 466 in the knife slide 370. When the screw 456 has been loosened the shaft 414 together with the arm 454 may be rotated to raise or lower the knife slide 370 to the desired starting position so that during the substantially constant throw of the knife slide the cutting edge 376 of the knife 30 will engage but not cut substantially into the cutting block 32.

As above explained, the driving shaft 94 (Figs. 2 and 5) rotates twice during each cycle of the machine and accordingly the connecting rod 432 is moved up and down twice during each cycle of the machine. Since it is desirable to cause the breasting knife 30 to be operated only once during each cycle of the machine the thrust bars 424 are held by the cam 446 secured to the countershaft 104 away from recesses 426 in the actuator 428 during the first up and down movement of the connecting rod 432 so that during such movement the knife 30 shall not be operated. Before the next up and down movement of the connecting rod 432, however, the cam 446 allows the spring 445 (Fig. 2) to move the lower ends of the thrust bars 424 into opposing recesses 426 of the actuator 428 with the result that the breasting knife 30 is lowered to breast the heel carried by the turret 22 from the loading station 26 to the breasting station 28 during the first half cycle of the machine.

The stopping of the turret 22 when the heel holding units 24 have arrived at their loading and breasting stations 26, 28 respectively is effected by a stop pawl 468 (Figs. 5 and 6) which is arranged to be engaged first by one and then by the other of a pair of plates 470 secured by screws 472 (Figs. 5, 6 and 7) to the box-like

brackets 142 one at each side of the turret. The stop pawl 468 is pivoted on a pin 474 (Fig. 5) carried by the central frame 74 and has pivotally connected to it a rod 476 which extends through a passage in the central frame and the lower end of which has secured to it a block 478. The stop pawl 468 is constantly urged clockwise as viewed in Fig. 5 to a position in which it is arranged in the path of movement of one or the other of the plates 470, by a compression spring 480 upper and lower ends of which engage the stop pawl and the central frame 74 respectively, a stud 482 fixed to the central frame limiting said clockwise movement of the pawl. The stop pawl 468 is swung counterclockwise (Fig. 5) away from the path of movement of the plate 470 by a lug 484 on the turret actuating arm 132, the construction and arrangement being such that when said arm swings counterclockwise from its position shown in Fig. 5 to cause the turret 22 to be rotated through 180°, the lug 484 releases the block 478 permitting the stop pawl 468 to be elevated by the action of the spring 480. The stop plate 470 at the rear of the turret will, as soon as the turret commences to rotate, move above the pawl 468 before the pawl can move into the path of movement of the plate, the pawl rising under the action of the spring 480 into the path of movement of the following plate after being disengaged by the plate leaving the breasting station 28. Rebound of the turret 22 from its loading and breasting stations 26, 28 respectively is prevented by a spring actuated pawl 486 (Fig. 6) which is pivoted on an eccentric bearing 488 adjustable in the central frame 74 and past which each plate 470 passes as it approaches its stopping position, said pawl being constructed to snap by the action of a spring 489 in behind the plate as soon as the plate has passed it.

In order to insure that loose heels or tools, for example, accidentally left upon the platform 36 of the turret 22 shall not be engaged by the knife 30 and/or the knife slide 370 and cause breakage of machine parts, the illustrative machine is provided with a pair of clearers or clearer arms 490 (Figs. 1, 2, 12 and 13) which swing forward over the platform at opposite sides and in advance of the knife 30 to remove said heels and/or tools from the platform. Each of the clearer arms 490 is fulcrumed or pivotally mounted upon a pin 492 (Figs. 12 and 13) secured to a carrier 494 which is secured to a pin 496 rotatably mounted in a lug 498 attached by screws 500 to opposite sides of the knife bracket 304.

Each of the carriers 494 is constantly urged by a spring 502 toward its idle or rest position in which a shoulder or abutment of the carrier is in engagement with a stop 504 fixed to the lug 498. The clearer arms 490 are constantly urged rearward by springs 506 against rolls 508 which are mounted upon extensions of the pins 492 which pivotally connect the knife actuating lever 420 to the links 416. During the cutting stroke of the knife 30 the rolls 508 travel along the rear edges of the clearer arms 490 causing them to swing forward about fulcrum pins 492 to their dash-line positions shown in Fig. 12, the construction and arrangement of the clearer arms being such that they move forward during the first part of the downward movement of the knife and reach their forward positions just as the knife reaches its lowest position. Should the clearer arms 490 as they swing forward over

the platform 36 engage articles upon the platform they will push such articles forwardly off the platform 36 and if said arms engage the top surfaces of said articles they will yield upward about the axes of the pins 492 and at the same time force the articles forward out of the path of movement of the knife 30 and the knife slide 370. The clearer arms 490 may be defined as fulcrumed upon the carriers 494 which are arranged to move upon the frame 498 to cause fulcrumed ends of the clearer arms to move yielding away from the platform when they engage articles upon the platform.

The one-revolution clutch 96 (Fig. 14) will now be described. The gear 86 which is rotatably mounted upon the clutch shaft 88 has secured to it a pair of studs 491 constructed and arranged to be engaged by a key 493 which has a recess 495 for receiving a ring 497 and is slidably mounted in a collar 499 fixed to the shaft. The ring 497 is spaced from the collar 499 and is pivotally connected to an arm 503, a pair of lugs 501 secured to the collar engaging rolls carried by the upper ends of arms 505 which are in parallel arrangement with the arms 503. The arms 503, 505 are secured to parallel pins 507, 509 pivotally mounted in the central frame 74, the pin 507 having secured to it a depending arm 511 upon the lower end of which is mounted a roll 513 shaped and arranged to engage a cam 515 secured to the countershaft 104. The depending arm 511 has secured to it a plate 517 held by a tension spring 519, opposite ends of which are attached to said arm and to the central frame 74, against a block 521 secured to an arm 523 rotatably mounted upon a bearing pin 525 carried by the central frame 74. Also fulcrumed upon the pin 525 is a bell crank lever 527 a horizontal arm of which comprises a flange 529 and has pivotally connected to it a link 531 which controls brake mechanism such as is disclosed in United States Letters Patent No. 2,552,544, granted May 15, 1951, on an application filed in the names of Harold E. Elliott et al. and also disclosed more in detail in a corresponding British Patent No. 642,008.

A vertical arm of the bell crank lever 527 is operatively connected by the link 530 to the bell crank lever 98 which as above explained is operated in response to movement of the treadle 50. When the treadle 50 is depressed the bell crank lever 527 swings clockwise and releases the brake (not shown) and moves the flange 529 downward until it engages the arm 523 which is constantly urged upward by a spring 533 thereby moving the block 521 away from the plate 517 carried by the arm 511 and thus causing the key 493 to move to the right as viewed in Fig. 14 into the path of movement of one of the studs 491.

During the operation of the machine the treadle 50 is automatically disconnected as above described and the cam 515 withdraws the key 493 away from the stud 491 engaged by the key, the link 531 at that time being raised to apply the brake to the clutch shaft 88. Since the clutch 96 and the braking mechanism are not claimed herein and may have substituted for them suitable other clutch and braking mechanisms of well-known construction no further description of the clutch and brake is deemed necessary.

When the machine is in its idle or rest position the heel grippers 44 of the heel holding unit 24 at the heel loading station 26 are in their open raised positions. The operator grasps a heel from a receptacle (not shown) at the left

of the machine and places it tread end down and breast rearward on the face of the cutting block 32 of such unit between the grippers 44, the heel being slid rearward until the breast of its top lift engages the edge 38 of the breast gage 34. As above explained, the grippers 44 are initially adjusted by turning the knurled nut 182 so that the heel will pass between the grippers which while seizing the heel serve to position said heel laterally on the cutting block 32.

While retaining hold of the heel the operator then depresses the treadle 50 causing during the first part of its downward movement the control rod 214 (Fig. 6) to be moved rearward thus permitting the grippers 44 to swing under the action of the tension springs 48 against opposite sides of the heel. As the treadle 50 is further depressed the breast gage 34, upon rearward movement of the two-part rod 268, is swung rearward by the action of the spring 280 (Figs. 1 and 3) from its gaging position over the cutting block 32 of the heel holding unit 24 at the loading position 26. If at this time should the operator decide that the heel is not properly positioned and/or clamped in the machine he may temporarily cease to continue to depress the treadle 50 until he has, by the use of the manually actuated gripper opening lever 233, released the heel and has again oriented and seized it to his satisfaction.

Upon continued depression of the treadle 50 the clutch 96 is tripped thereby causing the turret 22 to be power indexed 180°. During rotation of the turret 22 the stop pawl 468 (Figs. 5 and 6) is raised in readiness to be engaged by the plate 470 on the turret 22 which is moving from the loading station 26, and the cam roll 166 (Figs. 5, 7 and 8) connected with the bar 158 moves off the cam block 188, the heel grippers 44 being moved downward by the compression springs 58 to cause the heel to be forced with considerable pressure against the face 192 of the cutting block 32 of the front holding unit 44 of the turret.

As above explained, the shaft 94 (Figs. 2 and 5) which carries the crank 434 through which the knife 30 is operated rotates twice during each cycle of the machine. During the first rotation of the driving shaft 94 the thrust bars 424 are held by the cam 446 on the countershaft 104 out of engagement with the recesses 426 in the actuator 428 and no movement of the knife 30 takes place. After the heel holding unit 24, in which the heel has been positioned and seized, has reached the breasting station 28 the thrust bars 424 are moved into the recess 426 in the actuator 428 and during the second rotation of the driving shaft 94 the knife 30 is operated to breast the heel, chips trimmed from the heel falling down the passage 70 in the center of the turret 22 into a basket (not shown).

During the next cycle of the machine the cam roll 188 (Figs. 7 and 8) on the gripper opening lever 209 rides up the cam face 336 (Fig. 6) on the bracket 204 causing the grippers 44 to be moved away from the breasted heel, such action occurring just before the heel reaches the ejecting station 59, the knock-off arm 56 then striking the heel and thrusting it into the chute 60 when the heel has reached said ejecting station.

As the holding unit 24 from which the heel has been ejected approaches the loading station 26 the cam roll 186 on the lower end of the rod 170 extending down from the bar 158 travels upon the face 186 of the cam 188 causing the grippers 44 to be moved to their raised positions and the

cam roll 186 of the lever 178 rides onto the supporting face 198 of the lever 200 thus causing the grippers 44 to be further separated to facilitate insertion of the heel, which is to be next operated upon, in the heel holding unit.

Having thus described my invention, what I claim as new and desire to secure by Letters Patent of the United States is:

1. In a heel breasting machine, a platform, a pair of grippers spaced to receive between them a heel supported by said platform, means for effecting relative movement of said grippers in a path disposed generally parallel to a heel engaging surface of said platform to seize the heel, means for effecting relative movement between the platform on the one hand and the grippers on the other hand in a path disposed at substantially right angles to said first-named path to cause the seized heel to be clamped against the platform, and means for breasting the heel.

2. In a heel breasting machine, a platform, a pair of grippers spaced to receive between them a heel supported by said platform, means for moving the grippers toward each other to seize the heel, means for moving the grippers toward the platform to force the seized heel under substantial pressure against the platform, and means for breasting the heel.

3. In a heel breasting machine, a platform, a gage for positioning a heel lengthwise upon the platform, a pair of grippers each having a plurality of heel penetrating prongs, said grippers being spaced to receive between them a heel supported by the platform and having its breast in engagement with said gage, means for moving the grippers toward opposite sides of the heel to seize the heel, means for moving the grippers toward the platform to clamp under pressure the seized heel against the platform, and means for breasting the heel.

4. In a heel breasting machine, a support for a heel, a breast gage for positioning the heel lengthwise upon the support, grippers which are positioned at opposite sides of the heel, resilient means for urging said grippers toward each other and together toward the support, mechanism for moving the grippers against the action of said resilient means to open positions away from each other and to positions away from the support, means for rendering said mechanism ineffective to cause said grippers actuated by said resilient means to seize the heel and to clamp it against the support, and a knife for breasting the heel thus clamped.

5. In a heel breasting machine, a turret comprising a plurality of units each including a platform for supporting a heel and grippers between which a heel is placed upon the platform, means for automatically indexing said units between a heel receiving station in which the heels are positioned and clamped in said units and a breasting station in which said heels in said units are breasted, resilient means for constantly urging said grippers toward each other and together toward the platform, mechanism operated in timed relation with the turret for moving the grippers against the action of said resilient means away from each other and together away from the platform, and manually actuated means for rendering said mechanism ineffective to enable said grippers under the action of said resilient means to seize the heel and to clamp it against the platform.

6. In a heel breasting machine, a support for a heel, a breast gage for positioning the heel

lengthwise upon the support, grippers overlying said support and arranged to receive the heel between them, springs for urging said grippers toward each other, springs for urging the grippers toward the support, powered means for moving against the action of said springs the grippers to open positions away from each other and to elevated positions away from the support, manually operated mechanism for rendering the springs effective to cause the grippers to seize the heel and to clamp it against the support, and a knife for breasting the heel thus clamped.

7. In a heel breasting machine, a turret comprising a plurality of units each including a platform and grippers between which a heel upon the platform is placed, means for automatically indexing said turret between a receiving station in which the heels are positioned and clamped in said units and a breasting station in which said heels are breasted, resilient means for constantly urging said grippers toward each other and together toward the platform, mechanism operated in timed relation with the turret for moving the grippers against the action of said resilient means away from each other and together away from the platform, and manually actuated means preliminary movement of which renders portions of said resilient means effective thereby causing the grippers to be moved toward each other and further movement of which causes the turret to be indexed and other portions of said resilient means effective to cause the grippers to force the heel against the platform.

8. In a heel breasting machine, a support, means for positioning a heel upon the support, said means comprising a pair of grippers which are arranged above said support and between which the heel is placed, mechanism for moving said grippers equal distances toward each other to assist in positioning the heel upon the support and to seize the heel and for thereafter forcing the heel against the support, and a cutter for breasting the heel positioned and clamped upon the support.

9. In a heel breasting machine, a turret comprising a plurality of heel receiving units, means for automatically indexing the turret to move said units successively between heel receiving and heel breasting stations, means for positioning a heel in each of the units at the receiving station, said heel positioning means comprising a single breast gage which at all times is positioned adjacent to the heel receiving station and which is moved over the turret intermittently toward and away from said units at said heel receiving station, means for clamping a positioned heel in each of said units, a manually actuated member, and mechanism automatically operated in response to movement of said member for successively seizing the heel in one of the units at the heel receiving station, moving the breast gage away from said unit and indexing the turret and clamping the seized heel in said unit.

10. In a heel breasting machine, a rotatable turret comprising a plurality of heel receiving units, means for automatically indexing the turret to move said units successively between a heel receiving station and a heel breasting station, a single breast gage which at all times is positioned adjacent to the heel receiving station and is movable intermittently over the turret toward and away from said units at said heel receiving station, each of said units comprising means for positioning in said unit at said receiving station a heel in engagement with

said breast gage and for clamping said heel against movement in said unit, a manually actuated member, and mechanism operative in response to movement of said member for automatically operating said heel positioning and clamping means, moving the breast gage away from the unit at the heel receiving station, and rendering said indexing means active to index the turret.

10 11. In a heel breasting machine, a rotatable turret comprising a plurality of units each including a platform, means for automatically indexing said units successively between a heel receiving station and a heel breasting station, a breast gage movable with relation to a unit at the heel receiving station toward and away from a gaging position, each of said units comprising a pair of grippers between which the heel a breast of which is in engagement with said gage is placed, a manually actuated member, and mechanism operative in response to movement of said member for causing the grippers to seize opposite sides of the heel, then to effect movement of the breast gage away from said unit and to actuate said indexing means and thereafter to force the heel seized by said grippers with clamping pressure against the platform.

15 12. In a heel breasting machine, a turret comprising a plurality of units each including a platform and grippers between which is placed a heel upon said platform, means for automatically indexing said units between a heel receiving station and a heel breasting station, springs for constantly urging said grippers toward each other, springs for constantly urging the grippers collectively toward the platform, means cooperative with the turret for moving the grippers against the action of said springs away from each other and collectively away from the platform, a manually actuated member preliminary movement of which is adapted to render portions of said means inactive to enable the first-named springs to move the grippers toward each other to seize the heel against movement in its associated unit, secondary movement of said manually actuated member causing the turret to be indexed and other portions of said means to be rendered inactive to enable said secondary springs to force the grippers with considerable pressure against the platform, and a control lever operatively connected to said first-named portions of said means for moving the grippers apart against the action of said first-named springs after preliminary movement of said manually actuated member has been effected thereby enabling the operator to release the heel preparatory to repositioning it in said unit after it has been seized but before the turret has been indexed.

13. In a heel breasting machine, a turret comprising a plurality of units each including a platform for supporting a heel and a pair of grippers which are arranged above said platform and are spaced to receive said heel between them, a breast gage for positioning a heel lengthwise upon the platform, springs for forcing the grippers toward each other, springs for forcing the grippers collectively toward the platform, mechanism for moving the grippers apart and away from the platform against the action of said springs, means for automatically indexing said turret to move said units between a heel receiving station and a breasting station, and manually actuated means for rendering a portion of said mechanism ineffective to cause the grippers under

the action of the first-named springs to move toward each other and to cooperate with the breast gage in positioning the heel on the platform and to seize the heel and for thereafter rendering said indexing means active to index the turret and for rendering another portion of said mechanism ineffective to cause the grippers to be urged under the action of the second-named springs toward the platform to clamp the heel securely to said platform.

14. In a heel breasting machine, a support for a heel, a breast gage for positioning the heel lengthwise upon the support, spaced grippers overlying the support and movable toward and away from each other, springs for constantly urging the grippers toward each other, said grippers being movable toward and away from the support, springs for constantly urging the grippers toward the support, means constructed and arranged to move against the action of the first-named springs the grippers away from each other, means constructed and arranged to move against the action of the second-named springs the grippers away from the support, manually actuated mechanism movable initially a predetermined distance to render inactive the first-named means to cause the grippers to be forced by the first-named springs against the opposite sides of the heel, said manually actuated mechanism when moved beyond said predetermined distance being adapted to render the second-named means inactive to cause said second-named springs to move the grippers toward the support and accordingly to force the heel against said support, a hand lever connected to said first-named means for moving the grippers apart so long as the manually actuated mechanism has not been moved beyond said predetermined distance thereby releasing the heel preparatory to repositioning it upon the support.

15. In a heel breasting machine, a turret comprising a plurality of units each having a heel supporting face, means for positioning and clamping heels mounted upon said faces of the units, means for automatically indexing said units successively between a heel receiving station and a heel breasting station, a breasting knife, and means for operating said knife to breast heels at said breasting station, said turret having extending axially through it a bore which terminates at the supporting faces of said units and through which falls material trimmed from the breasts of heels.

16. In a heel breasting machine, a platform having a heel supporting face, means for positioning a heel lengthwise and widthwise upon said face, means for clamping the positioned heel upon said face, a knife, a guide for directing the knife in a path extending generally heightwise of the heel, mechanism for imparting to the knife a predetermined throw in said path, means for initially adjusting the guide about a fixed axis which lies in said face of the platform and extends generally transversely of the heel in the vicinity of its breast, and power operated mechanism for reciprocating the knife in said path from a predetermined position in said guide and for stopping irrespective of the angular adjustment of the guide said knife in the vicinity of said axis to breast the heel.

17. In a heel breasting machine, a platform having a face, means for positioning a heel lengthwise and widthwise upon said face, means for clamping the positioned heel upon said face,

a knife, a frame for guiding the knife in paths extending generally heightwise of the heel, mechanism for imparting to the knife a predetermined throw, means for adjusting the frame about an axis which lies substantially in said face of the platform and extends generally widthwise of the positioned heel in the vicinity of its breast, powered mechanism operatively connected to the knife for moving the knife in said path from starting positions in said frame to positions in which the knife stops approximately at said axis, and resilient means for effecting movement of the knife back to its starting position, said mechanism being constructed and arranged to control the speed of movement of the knife to its starting position under the action of said resilient means.

18. In a heel attaching machine, a platform, means for positioning a heel upon and clamping it against said platform, a breasting knife having a cutting edge, a guide having ways in which said knife is slidably mounted, means for moving said knife along said ways in a predetermined path in which the central point of the cutting edge of the knife at the end of its cutting stroke engages said platform substantially at a predetermined point, mechanism for moving said guide into different adjusted positions about an axis extending along said platform and transversely of the heel through said point, said mechanism comprising links which are pivotally connected to the knife, and a lever one end of which is pivotally connected to the links for movement about a shifting axis which is parallel to the first-named axis and which when the cutting edge of the knife engages said platform is arranged generally in said first-named axis.

19. In a heel breasting machine, a platform, means for positioning a heel upon and clamping it against said platform, a breasting knife having a cutting edge, a guide having ways in which the knife is slidably mounted, means for moving the knife along said ways in a predetermined path at one end of which the cutting edge of the knife engages said platform, mechanism for moving the knife along said ways, means for initially adjusting the guide into fixed operating positions about an axis extending transversely of the heel and along said platform substantially through a point of engagement of the central point of the cutting edge of the knife with the platform, said mechanism comprising a pair of links and a pin for pivotally connecting the links to the knife, said pin having concentric and eccentric portions upon which the knife and the links respectively are mounted, and means for initially rotating said pin into different adjusted positions upon the knife to move said knife into different positions in said ways with relation to said links.

20. In a heel breasting machine, a platform, means for positioning a heel upon and clamping it against said platform, a knife, a heel holder, a guide having ways along which the knife holder is reciprocated, a fixed bracket upon which the guide is mounted, said guide being movable into different angular positions upon said bracket about an axis extending transversely of said heel and along said platform, manually actuated mechanism for angularly adjusting the guide upon the bracket about said axis, means for locking the guide to the bracket and for releasing said guide for movement upon the bracket, and friction means for holding the guide against displacement from its position upon the bracket when said locking means is released and an oper-

ator has released manually control of said mechanism.

21. In a heel breasting machine, a turret comprising a plurality of heel receiving units, means for automatically indexing said units successively between a heel receiving station and a breasting station, each of said units comprising a platform for supporting a heel and spring actuated grippers for seizing opposite sides of the heel and forcing said heel against the platform, power-operated means, a clutch, a breast gage movable in timed relation with the turret into and away from an active position over the units at the loading station, mechanism for controlling movement of said spring-actuated grippers away from each other and away from their associated platforms in response to indexing movement of the turret, and manually actuated means associated with said mechanism for rendering portions of said mechanism ineffective to cause the grippers to move toward each other to clamp the heel in the unit at said receiving station then to cause the breast gage to swing away from the unit and thereafter to trip the clutch to cause said power-operated mechanism to index the turret and accordingly to render other portions of said control mechanism ineffective thereby causing the gripped heel to be clamped against the platform.

22. In a heel breasting machine, a platform having a face, means for positioning a heel upon and clamping it to said platform, a knife having a cutting edge, a guide for controlling movement of the knife in a path which is disposed generally heightwise of the heel and in which a cutting edge of the knife moves into engagement with said face of the platform, a pair of spaced brackets which are arranged at opposite sides of the guide and have arcuate slots centered about an axis lying substantially in said face of the platform and extending generally widthwise of said heel in the vicinity of its breast, said guide having at its opposite sides arcuate lugs which fit slidably in said slots of the brackets, means for moving the lugs and accordingly the guide lengthwise of said slots, means for locking the guide to said bracket and for releasing the guide for adjustment in said bracket, a power-operated lever, links upper ends of which are pivotally connected to the knives and lower ends of which are pivotally connected to the lever about a shifting axis which when the cutting edge of the knife is in engagement with the face of the platform is in substantial alignment with the axis about which the guide is adjusted irrespective of the angular adjustment of the guide.

55

23. In a heel breasting machine, a turret having a plurality of heel receiving units, means for positioning and clamping heels in said units, means for breasting heels positioned and clamped in said units, means for indexing the turret about an axis, means for releasing the heels in said units after they have been breasted, and an ejector for successively removing the released breasted heels from the units as the units are indexed, said ejector comprising an actuator which is movable toward and away from said axis, and an arm which is carried by the actuator and is movable together with the actuator toward and away from the axis to sweep heels from the turret and which is also yieldable from an active position upon the actuator substantially at right angles to its movement toward and away from said axis to insure against breakage of parts should portions of the units engage said arm.

24. In a heel breasting machine, a platform, means for positioning and clamping a heel upon the platform, a knife movable in a predetermined path to breast the heel, means for operating the knife, a fixed frame, a stop, carriers which are pivotally mounted upon the frame at opposite sides of the knife, clearers which are fulcrumed upon the carriers, and springs secured to the carriers and to the frame for constantly urging the carriers to normal positions in which the carriers engage the stops and in which fulcrumed ends of the clearers are in lowered positions with relation to the platform, said clearers being operated in timed relation with the knife to swing over the platforms during the first portion of the breasting stroke of the knife to force any articles accidentally left on the platform from the platform and out of the path of movement of the knife and its operating mechanism, said carriers being arranged to move upon the frame against the action of the springs to cause the fulcrumed ends of the clearers to move yieldingly against reaction of articles engaged by the carriers away from the platform as they swing over said platform.
